CARAFE

Alfred D. Sterges, Los Angeles, Calif., assignor to Purex Corporation, Ltd., South Gate, Calif., a corporation of California

Continuation of design application Ser. No. 60,607, May 16, 1960. This application Oct. 16, 1961, Ser. No. 67,074

Term of patent 14 years

(Cl. D58—8)

FIG. 1.

FIG. 2.

FIG. 4.

FIG. 3.

FIG. 1 is a front elevational view of a carafe, showing my new design;

FIG. 2 is a side elevational view thereof;

FIG. 3 is a cross-sectional view thereof taken on line 3—3 of FIG. 1; and

FIG. 4 is a top plan view thereof.

This application is a continuation of the earlier application of Alfred D. Sterges entitled plastic carafe, Serial No. D. 60,607, filed May 16, 1960, which is now abandoned.

I claim:

The ornamental design for a carafe, substantially as shown and described.
